OFFSET PREVENTING IN PRINTING

Virgil G. Green and Eric Gustafsson, Chicago, Ill.,
assignors to Binks Manufacturing Company,
Chicago, Ill., a corporation of Delaware

Application November 27, 1935, Serial No. 51,742
Renewed February 2, 1938

22 Claims. (Cl. 101—420)

Our invention relates to a method for avoiding the production of offset (or smudge) by the piling of sheets upon one another after their imprinting, both for eliminating the need of having so-called "slip sheets" temporarily inserted between the consecutive sheets and for permitting a rapidly successive imprinting of another color on the same sheet.

For such offset-preventing it is already customary on cylinder printing presses to apply a liquid ink-repellent or ink-drying material to the freshly imprinted sheet by spraying such material (either downward or upward, according to the direction in which the freshly made imprint on the sheet faces) upon the sheet, so as to coat or at least stipple the entire imprint with the ink-repellent.

This may be done by having the freshly imprinted sheet pass under either a single wide-angled spray or under a row of sprays while that sheet is being conveyed to the delivery table on which the sheets are to be stacked; or the spray-coating (or spray-filming) of each sheet may be done after that sheet is already on the stack.

In practice, this already customary procedure of spray-coating the freshly imprinted face of a sheet with an offset-eliminating liquid has the following objections:

(a) Since no single spray device can project a spray of uniform density over an imprint of considerable area, a spraying of an adequate amount of offset-preventing material on some parts of the imprint (as for example on those near the side edges of the sheet conveyer) can only be obtained by also depositing a highly excessive amount of material on other portions of the imprint. Consequently, the consumption (and hence cost) of this material is all out of proportion to the quantity which should be adequate, and the excess of such deposited material often interferes with the clarity of a later imprint of another color on the same sheet.

(b) This excessive consumption of offset-preventing material also requires a correspondingly large consumption of compressed air for atomizing and propelling the spray, together with adequate material-supply provisions which often occupy valuable space in the printing establishment.

(c) The excess of such material deposited on some sheet portions also retards the drying of that material, unless the latter is of a type which requires heating provisions for its use, thereby delaying the successive imprinting of the same sheet with another color.

(d) The highly excessive quantity of offset-preventing material also produces a correspondingly increased amount of fumes, thereby requiring extensive fume exhaust provisions such as might not be needed in the same establishment if only the operatively required amount of such material were sprayed, and also permitting the excessive fumes to damage parts of the printing press.

Our present method aims to overcome all of the above recited objections, and is based largely on the following observations:

(1) When a modern spray gun, with a given adjustment, is so far from a surface toward which the gun is pointed that the spray no longer impacts against that surface, the spray becomes more highly atomized, and with relatively light sprayable materials, such as are suitable for offset-prevention, the resulting misty spray becomes so diffused as to descend only slowly by gravity.

The process is capable of using any of the well known substances heretofore used for preventing offsetting in printing, such as those referred to and described in the United States Patent No. 2,007,404, granted July 9, 1935, to John MacLaurin, in the United States Patent No. 2,078,790, granted April 27, 1937 on an application filed December 24, 1931 by Edmond H. Bucy, in the British Patent #439,078, granted to Jens A. Paasche and accepted November 28, 1935, and in the French Patent #784,826 granted to Jens A. Paasche, delivered May 6, 1935.

(2) When such a spray is emitted only momentarily and along an inclined axis, the puff of spray forms a misty cloud which is spread out somewhat horizontally during its descent.

(3) With a modern spray gun, air continues to issue from the gun for a short time after the discharge of material from the gun has ceased. Consequently, if spray were projected only momentarily in a puff forming a temporarily floating cloud, this later issuing air additionally atomizes and spreads the cloud and also moves the cloud farther away from the gun.

(4) When such a momentary puff of atomized material is projected toward the upper face of a sheet at a velocity which is insufficient for having the resulting misty cloud impact against the sheet, the air below this cloud will slowly spread the cloud of mist to a larger horizontal area.

(5) When a freshly imprinted sheet is being dropped flatwise on a previously imprinted one, the edge portions of the descending sheet curl up and the dropped sheet consumes an appreciable time in flattening down on the previous one, pre-

sumably because the freshly dropped sheet has to compress and gradually squeeze out the air between it and the sheet previously piled on the delivery table.

- 5 (6) If a cloud of mist has been formed freely above a previously stacked sheet, as recited in the next to the last preceding paragraph, and a freshly imprinted sheet is dropped above that cloud before the cloud has gradually descended 10 on the previously stacked sheet the squeezing out of the air between the two sheets during the descent of the freshly imprinted one flattens the cloud and spreads the cloud out horizontally to a greatly increased horizontal area. Consequently, a cloud of initially much smaller horizontal area than the imprinted face portion of a sheet below it may have the material particles of that cloud distributed over this entire imprinted face.
- 20 (7) Since the air thus squeezed out between the dropping sheet and the stationary one below it is of enormously greater volume than the air emitted from the spray device for projecting the puff of spray, the sprayed offset-preventing liquid 25 is much more finely atomized than when sprayed directly on a stationary sheet, thereby making a relatively quite small quantity of such material adequate for causing the freshly dropped sheet to be supported temporarily by the many spaced 30 particles of this material while the residual air between the two sheets aids in drying the last made imprint.

Illustrative of the manner in which we utilize the above observations.

- 35 Fig. 1 is a fragmentary rear end elevation of a cylinder-type printing press provided with an attachment for spraying puffs of offset-preventing material in timed relation to the operation of the press, with dotted lines showing the path of 40 the projected spray and the initial outline of the resulting cloud of the sprayed material.

Fig. 2 is a fragmentary side elevation of the same press, taken from the right-hand side of Fig. 1.

- 45 Fig. 3 is a plan view of the delivery table of the same press and of the spraying attachment, with dotted lines showing the emitted spray and the initial outline of the resulting cloud.

Fig. 4 is a reduced rear end view of the delivery 50 table of the press when this has a number of sheets already stacked on it, and showing the next imprinted sheet in the position from which that sheet is dropped, and including a dotted outline showing the maximum initially advisable 55 height of the cloud of offset-preventing material below the said freshly imprinted sheet.

Fig. 5 is a view similar to Fig. 4, but taken after the dropping sheet has descended part way toward the stack of sheets below it, showing the 60 horizontal spreading of the said cloud.

Fig. 6 is a view allied to Fig. 4, showing the projecting of a suitable cloud of offset-preventing material by a spray device positioned for projecting a spray horizontally.

65 Fig. 7 is a fragmentary side elevation of the rear end of a cylinder press in which each freshly imprinted sheet is dropped from the arms of a pivoted sheet-delivery mechanism.

In the drawings, Figs. 1 to 3 show portions 70 of a conventional printing press in which each sheet, after it leaves the cylinder C slides down an inclined guide 1, is then slid rearwards by a traveling sheet feeder 2 propelled by a rocker arm 3 of the press, and in which this sheet is released (by the usually provided means) when it

is directly above the stack S of previously imprinted sheets on the delivery table T of the press.

Fastened to one side of the rearward part of the press, as by brackets B attached to a rear leg L of the press, is a riser R, the upper end of which supports a material container 4 from which material can flow by gravity to a spray device 5 to which a hose A also supplies compressed air. This spray device preferably is supported from the riser R by a bracket 6 which can be adjusted as to its position both longitudinally and rotationally of the said riser, and the spray device also preferably is pivoted to the said bracket (as on a horizontal shaft 7) so that the user can readily vary the direction in which the spray (shown in dotted lines at 8) is emitted.

To operate the spray device, we connect it to an electric actuating device 9 (of which many commercial solenoid types are well known) to 20 which circuit wires W lead from a switch 10 which has an arm 10a adapted to be engaged by the rocker arm 3 (or by a trip arm 3a fastened to the latter) when the rocker arm is momentarily near its most forward position. Many such solenoid actuated spray device have long been known, as attested for example by the Burdick British Patent #4,211 of 1905 and by the Gradolph and Mueller (U. S.) Patent #1,616,823.

When the spray device is adjusted for emitting 30 a spray with a velocity insufficient for impacting the spray upon the sheet stack S, the spray spreads as its velocity diminishes; and when this spray has been emitted as a mere puff, the resulting mist forms a cloud, which (with the spray device constructed for a fine atomization) is so light as to descend only quite slowly by gravity. Owing to this lightness, the cloud cannot readily force the air below it out of its way, so that the resistance of this air to compression causes the 40 cloud to spread in horizontal area to form a cloud of mist M.

With a proper adjustment of the spray device, which can readily be made after a few trials, this 45 cloud will be disposed somewhat below the position (shown in Fig. 4) from which the next freshly imprinted sheet F is dropped after that sheet has been moved rearward by the sheet feeder 2. During the descent of this sheet by gravity (in what the printers call "air dropping") the 50 squeezing out of air between that sheet and the sheet stack S below it forces additional air upwards into the cloud, so as to spread this first to the larger horizontal area M¹ of Fig. 5 and to still larger area as the dropping sheet approaches the 55 said stack more and more. Moreover, with an unusually large imprint area, the spray may be flattened by having air emitted also from the usual horns 5a (Fig. 1) of the spray device to spread the mist more widely before the dropping 60 sheet strikes it.

With the switch thus disposed so that it will be actuated only during a small fraction of the initial part of the rearward movement of the arm 3 which propels the sheet-sliding traveler 2, 65 the resulting puff of spray, although emitted at a velocity inadequate for propelling the spray all the way toward the sheet stack S, has ample time for spreading into a cloud disposed below the elevation from which the next sheet will be 70 dropped. Consequently, a quite simple mechanism suffices for our purposes.

Moreover, we have found in practice that with our here presented method the quantity of ink-repellent (or other offset-preventing) liquid 75

needed for a given imprint is only a quite small percentage of what would be required by the previously customary practice of directly spraying the material against a sheet—as for example, 5 only about three percent. Owing to this small material consumption, a correspondingly small material container 4 suffices for a day's run of a press, so that we avoid the heretofore customary need of having an enormously larger material

10 receptacle on an adjacent part of the floor (where it often is in the way of the press operator) and also eliminates the need of mechanical means for forcing the material from such a receptacle to the spray device.

15 Consequently, we can readily employ a gravity feed from the container 4 through a hose H to the spray device, and our entire installation can readily be detached from a given printing press by merely detaching the wires W from the switch 20 on that press and loosening the clamps B¹. This permits the same equipment to be transferred speedily to another press when the latter is provided with similar brackets B and also has a suitably disposed switch 10.

25 Owing to the extensive diminution of the required amount of offset-preventing material, we also correspondingly reduce the quantity of fumes produced by any such material, so that in a well ventilated printing establishment little or no 30 fume-exhaust provisions will be needed. Furthermore, by directing the projected spray somewhat rearwardly with respect to the printing press, we eliminate the risk of having the offset-preventing material gum or damage any operative 35 part of the press.

Moreover, if the imprint is on the side of the sheet which faces downwards during the dropping of the sheet, the spray device can readily be adjusted in position so as to dispose the cloud of 40 material somewhat lower, if desired. Thus, Fig. 7 shows portions of a printing press in which the sheet is received from the cylinder C by delivery arms 12 which swing the freshly imprinted sheet over the previously stacked ones with the imprint facing downward.

45 So also, our method can be employed without any downward directing of the projected spray, so long as this is directed for producing a mist cloud of the material above the last previously 50 stacked sheet and in the path through which the next imprinted sheet drops upon the stack. Thus, Fig. 6 shows such a cloud M² as produced by a spray device 5a which flattens the projected spray along a horizontal plane and projects this spray 55 along a horizontal axis across which each air-dropped sheet will move during its descent.

In practice, the forcing of air through a mist hovering above the imprint on an already stacked sheet expedites the evaporation of the liquid content of the particles of the mist, so that with the apparatus suitably adjusted, each such mist particle precipitates its solid content on the sheet in a nearly dry form. Consequently, if the material in the sprayed solution was a dextrin or other 60 common constituent for adhesives, each such deposited particle will instantly adhere to the sheet and will then be further dried by the air which moves over it during the completion of the decent of the next sheet. However, offset is likewise prevented even on the top of the last stacked sheet 65 because the mist gradually descends and upon that sheet, so that our method is not limited for use on sheets upon which others are thereafter to be stacked.

70 We claim as our invention:

1. A method of preventing offsetting in printing wherein imprinted sheets are consecutively dropped to form a stack, comprising the steps of momentarily puffing an atomized spray of offset preventing material to form a misty cloud above the last stacked sheet, and dropping the next sheet against said cloud to spread it and cause a distribution of the particles of the cloud over the surface of the last stacked sheet. 5

2. A method of preventing offsetting in printing wherein imprinted sheets are consecutively dropped to form a stack, comprising the steps of momentarily projecting a spray of offset preventing material part way toward the last stacked sheet to form a misty cloud above said last stacked sheet, and dropping the next sheet against said cloud to spread it and cause a distribution of the particles of the cloud over the surface of the last stacked sheet. 10

3. A method of preventing offsetting in printing wherein imprinted sheets are consecutively dropped to form a stack, comprising the steps of momentarily projecting a spray of offset preventing material part way toward the last stacked sheet to form a misty cloud of less horizontal 20 spread than the imprinted portion of the last stacked sheet and above said last stacked sheet, and dropping the next sheet against said cloud to spread it and cause a distribution of the particles of the cloud over the surface of the last 25 stacked sheet. 30

4. A method of preventing offsetting in printing wherein imprinted sheets are consecutively dropped to form a stack, comprising the steps of creating a cloud of finely atomized offset preventing material of less horizontal spread than the imprinted portion of the last stacked sheet and above the last stacked sheet and in the path through which the next sheet is dropped, and dropping the next sheet against said cloud to 40 squeeze it and the air between the last stacked sheet and the next sheet during the descent of the latter whereby the material particles of the cloud are distributed over a larger horizontal area than said cloud initially had and whereby the 45 particles will contact the opposed faces of the said two sheets.

5. A method of preventing offsetting in printing wherein imprinted sheets are consecutively dropped to form a stack, comprising the steps of 50 momentarily puffing an atomized spray of offset preventing material to form a misty cloud above the last stacked sheet and below the drop-starting position of the next sheet prior to the feeding of said next sheet to said position where the 55 cloud will momentarily hover above the last stacked sheet, and dropping the next imprinted sheet against said cloud whereby the forcing out of the air between the last stack sheet and the next sheet will increase the atomization of the 60 cloud and spread the particles of material over a larger horizontal area than that of the cloud.

6. A method of preventing offsetting in printing wherein imprinted sheets are consecutively dropped to form a stack, comprising the steps 65 of momentarily projecting a finely atomized spray of liquid offset preventing material toward the last stacked sheet prior to the approach of the next sheet to form a cloud which momentarily hovers over said last stacked sheet and in the 70 path of the next sheet, and dropping the next sheet against said cloud for forcibly moving the air through said cloud to spread the cloud particles further apart and to evaporate the liquid content of the particles. 75

7. A method of preventing offset in printing wherein imprinted sheets are consecutively dropped to form a stack, comprising the steps of momentarily projecting a finely atomized spray of offset preventing material toward the last stacked sheet to form a misty cloud initially hovering above said last stacked sheet and in the path through which the next imprinted sheet is to be dropped and with an areal extent less than that of the imprinted surface portions of said sheets, and dropping the next sheet against said cloud to spread it and cause a distribution of the particles of the cloud over the surface of the last stacked sheet.
- 15 8. A method of preventing offsetting in printing wherein imprinted sheets are consecutively dropped to form a stack, comprising the steps of momentarily projecting a finely atomized spray of offset preventing material toward the last stacked sheet at a velocity insufficient for impacting the sheet but sufficient for propelling the spray particles into the path through which the next imprinted sheet drops to form a cloud above the last stacked sheet, and dropping the next sheet against said cloud to spread it and cause a distribution of the particles of the cloud over the surface of the last stacked sheet.
9. A method of preventing offsetting in printing wherein imprinted sheets are consecutively dropped to form a stack, comprising the steps of momentarily projecting the finely atomized spray of offset preventing material toward the last stacked sheet to form a misty cloud of less area than said sheet, timing said spray projection to create said cloud before the next imprinted sheet reaches the position from which it is dropped, and dropping the next sheet against said cloud to spread it and cause a distribution of the particles of the cloud over the surface of the last stacked sheet.
10. A method of preventing offsetting in printing, comprising the steps of creating a cloud of finely divided particles from offset preventing material at a locus spaced from the surface of a previously printed sheet, and flattening said cloud by so dropping a successively printed sheet upon said cloud as to cause it and the particles thereof to spread at least over the whole area of the imprinted surface portion of the printed sheet.
- 50 11. A method of preventing offsetting in printing, comprising the steps of creating a cloud of finely divided particles from offset preventing material at a locus above the surface of a previously printed sheet and with a lesser areal extent than the area of the imprinted portion of said sheet, and so moving a successively printed sheet through said locus toward said previously printed sheet as to increase the area of said cloud and to cause the particles to spread at least over the entire area of the imprinted surface portion of the printed sheet.
12. A method of preventing offsetting in printing, comprising the steps of so spraying an offset preventing material in liquid condition as to provide a cloud of finely divided solid forming particles at a locus above the surface of a previously printed sheet and with a predetermined areal extent relative to the area of the imprinted portion of the sheet, and so moving a successively printed sheet through said locus and against said cloud as to cause it and the particles thereof to spread at least over the entire area of the imprinted surface portion of the printed sheet.
- 75 13. A method of preventing offsetting in printing, comprising the steps of so spraying an offset

preventing material in liquid condition and so projecting a jet of air therewith as to produce a cloud of finely divided particles at a locus above the surface of a previously printed sheet and with a lesser areal extent than the area of the imprinted portion of said sheet, and so moving a successively printed sheet through said locus toward said previously printed sheet as to cause said cloud to increase in area and to cause the particles to spread at least over the entire area of the imprinted surface portion of the printed sheet.

14. In a method of printing and delivering printed sheets, comprising the steps of delivering printed sheets in succession in given time intervals, creating a cloud of finely divided particles from offset preventing material in each interval between the delivering of sheets, in the path thereof and at a locus above the surface of the delivered previously printed sheet and with a given areal extent less than the area of the imprinted portion of said sheet, and causing the successively delivered printed sheet to so pass through said locus toward said previously printed sheet as to spread said cloud to cause the particles thereof to at least cover the entire area of the imprinted surface portion of said printed sheet.

15. A method of preventing offset in printing during the delivery of consecutively imprinted sheets, comprising the momentary puffing of a finely atomized spray of offset preventing material with air in a direction toward the imprinted surface of a delivered sheet and with insufficient force to cause an impact of the particles upon said surface so as to effect a cloud of finely divided particles at a locus spaced from said surface, and projecting sufficient air after the discharge of said spray as to cause a spreading of said cloud.

16. A method of preventing offset in printing which comprises the steps of creating a cloud of fine particles from offset preventing material opposite a face of a printed sheet and of less areal extent than said sheet, and then squeezing said cloud between said sheet and the next printed sheet as the latter is moved toward the former to cause the cloud to be spread over the imprinted surface portion of the printed sheet.

17. A method of preventing offsetting in printing wherein imprinted sheets are consecutively delivered to form a stack, comprising the steps of projecting a spray of finely atomized liquid offset preventing material toward the last stacked sheet to form a cloud above said sheet of less areal extent than the area of the imprinted portion of said sheet and in the path of movement of the next sheet, and so moving said next sheet against said cloud as to squeeze said cloud out to cover the whole area of said imprinted portion of the last stacked sheet.

18. A method of preventing offsetting in printing comprising the steps of spraying an offset preventing material in a fluid condition for a given interval of time, projecting a jet of air therewith for a greater interval of time and including the spray interval of time so as to produce a cloud of finely divided particles at a locus above the surface of a previously printed sheet and with an areal extent less than the area of the imprinted portion of said sheet, said projecting of said jet of air including the movement of a portion of the air following the sprayed material which blows through said cloud to assist in the spreading and the drying of the particles.

thereof, and so moving a successively printed sheet through said locus as to cause a lateral extension of said cloud and to cause the particles thereof to spread at least over the entire area of the imprinted surface portion of the printed sheet.

19. The method of preventing offset between imprinted sheets which are consecutively air-dropped upon one another from a predetermined drop position to form a stack, which comprises the step of producing a fine misty cloud of a solution containing a solid forming constituent adapted to form spacer particles on the uppermost stacked sheet, in such a manner that the cloud floats above the last named sheet and at least mainly below the said position; and the step of thereafter dropping the next sheet from said position so that the squeezing out of air between said sheet during the descent thereof will spread the cloud horizontally and cause the evaporation of solvent from the particles constituting the cloud.

20. The method of preventing offset between imprinted sheets which are consecutively air-dropped upon one another from a predetermined drop position to form a stack, which comprises the steps of producing a fine misty cloud of a solution containing a solid forming constituent adapted to form spacer particles on the uppermost stacked sheet, in such a manner that the cloud floats above the last named sheet and at least mainly below said position; blowing air against said cloud and toward the upper face of said stacked sheet; and dropping the next

sheet from said position so that the squeezing out of air between said sheet during its descent will spread the cloud horizontally and cause the evaporation of solvent from the particles constituting the cloud.

21. A method of preventing offset between consecutively printed and thereafter stacked sheets, comprising the steps of transforming a quantity of a liquid, containing a solid forming material suitable for sheet-spacing particles, into a misty 10 cloud spaced upwardly from and opposite only a substantially central portion of a freshly imprinted stacked sheet, and so moving the next printed sheet through the locus of said cloud and toward the aforesaid sheet as to spread the 15 cloud at least over the entire imprinted area portion of the first mentioned sheet.

22. The method of preventing printing offset by the depositing, upon a horizontal freshly imprinted sheet, of particles of the solid forming 20 constituent of a solution thereof, which comprises the projecting of a spray of a quantity of such solution toward the upper face of the said sheet into the form of a cloud spaced from said sheet; and causing forcibly moved air to elongate the 25 paths along which the spray particles move to the sheet, and to enhance the evaporation of solvent from the said particles during their travel through the said elongated paths, so as to effect a substantial drying of the said particles by the 30 time they reach the sheet.
